UNITED STATES PATENT OFFICE.

WALTER ANDERHUB, OF ZURICH, SWITZERLAND.

TURBINE AGGREGATE COMPRISING AN AHEAD TURBINE AND AN ASTERN TURBINE.

Application filed July 23, 1923, Serial No. 653,293, and in Switzerland August 4, 1922.

The invention relates to improvements in steam-turbine aggregates comprising an ahead turbine and an astern turbine.

It is a known fact that the economical utilization of the steam in the last stages of steam turbines that have to deal with large quantities of steam presents difficulties as the length of the blades and the diameter of the rotor respectively cannot be chosen too large owing to the strength of the material employed. In order to overcome these difficulties it has already been proposed to subdivide the stream of steam leaving a low pressure stage of a steam turbine into portions and to utilize these in separate runner wheels. Such an arrangement, however, requires an essential lengthening of the steam turbine. This is a serious drawback especially in such cases where the turbines have to be arranged in a limited space, as is for instance the case with steam turbine driven locomotives, on which besides the ahead turbine an astern turbine has to be arranged within the given clearance gauge. With vehicles of this type the ahead turbine and the astern turbine are preferably arranged to both sides of the longitudinal axis and transverse to the latter. The arrangement of the comparatively short astern turbine does not present any difficulty, whereas the substantially longer ahead turbine can only be lodged with great difficulties within the available limited space. In order to overcome this difficulty in locomotives, I have constructed a turbine aggregate comprising an ahead turbine and an astern turbine contained in separate casings and in which the steam is subdivided in front of at least the last stage of the ahead turbine into two portions that are caused to work in different runner wheels, shows according to the present invention the feature that those runner wheels of the ahead turbine to which one of said portions is supplied are arranged within the casing of the astern turbine. By this means the ahead turbine is not appreciably longer than the ahead turbine of an aggregate of the ordinary type in which the quantity of steam is not subdivided, and the lengths of the blades remain within reasonable limits owing to the subdivision of the steam.

Preferably the last runner wheel of the astern turbine and the last runner wheel of the portion of the ahead turbine arranged in

the casing of the astern turbine discharge into an exhaust space common to both wheels.

A constructional example of the subject matter of the present invention is illustrated partly in a longitudinal section and partly in elevation on the accompanying drawing which shows a turbine aggregate for locomotives.

In this drawing 1 denotes an ahead turbine and 2 an astern turbine. These turbines serve to drive a shaft 3 on which a pinion 16 is mounted. The latter operates in a well known manner with toothed gearing (not shown) transmitting power to the driving axles of the locomotive. The ahead turbine is arranged within a casing 10 provided with an inlet branch 4 and an outlet branch 5. The astern turbine 2 is contained in a casing 13 having an inlet branch 6 and an outlet branch 7. The quantity of steam leaving the last but one stage of the ahead turbine 1 is subdivided into two portions of which the one is supplied to a runner wheel 9 while the rest is conducted by means of a pipe 11 to a runner wheel 12 situated in the casing 13 of the astern turbine. The runner wheel 12 of the forward driving turbine and the last runner wheel 14 of the astern or reversing turbine discharge into an exhaust space 15 common to both. The runner wheels 9 and 12 form together the last stage of the ahead turbine 1.

Preferably a shut-off valve 17 is inserted in the pipe 11 to provide that when the ahead turbine 1 runs under partial loads, in which case the efficiency of the last stage is low, all the steam is supplied to the runner wheel 9 upon a closing of the shut-off valve, the wheel 9 working then also with a comparatively good efficiency.

Claims:

1. A turbine aggregate for locomotives, comprising an ahead turbine having a casing and a plurality of runner wheels, an astern turbine having a separate casing and a runner wheel of the ahead turbine inclosed in said separate casing, a shaft common to both turbines, means on said shaft between the turbines to transmit power to the locomotive, and a pipe communicating with a space in the ahead turbine situated in front of the last stage of said turbine and conducting a portion of the steam from said space to the runner wheel which is arranged within the

- casing of the astern turbine, the last mentioned runner wheel working in parallel with the runner wheels arranged within the ahead turbine that are impinged by the portion of the steam that remains in the ahead turbine.
- 5 2. A turbine aggregate for locomotives, comprising an ahead turbine having a casing and a plurality of runner wheels, an astern turbine having a separate casing and a runner wheel of the ahead turbine inclosed in said separate casing, a shaft common to both turbines, means on said shaft between the turbines to transmit power to the locomotive, a pipe communicating with a space in the ahead turbine situated in front of the last stage of said turbine and conducting a portion of the steam from said space directly to the ahead runner wheel which is arranged within the casing of the astern turbine, the last mentioned runner wheel working in parallel with the runner wheels arranged within the ahead turbine that are impinged by the portion of the steam that remains in the ahead turbine, and a shut-off member inserted in said conduit pipe permitting a cutting off of the runner wheel arranged within the casing of the astern turbine when the ahead turbine runs under partial loads.
- 10 3. A turbine aggregate for locomotives, comprising an ahead turbine having a casing and a plurality of runner wheels, an astern turbine having a separate casing and enclosing a runner wheel of the ahead turbine, said runner wheel having an exhaust space common with the astern turbine, a shaft common to both turbines, a pinion on said shaft, between the turbines, to transmit power to the locomotive and a pipe communicating with a space in the ahead turbine situated in front of the last stage of said turbine and conducting a portion of the steam from said space to the runner wheel which is arranged within the casing of the astern turbine, the last mentioned runner wheel working in parallel with the runner wheels arranged within the ahead turbine that are impinged by the portion of the steam that remains in the ahead turbine.
- 15 4. A turbine aggregate comprising an ahead turbine having a casing and a plurality of runner wheels therein, a reversing turbine consisting of a separate casing and a plurality of runner wheels therein one of which operates with the ahead turbine, a

shaft common to both casings and all runner wheels, a pinion on said shaft between the casings, and a pipe communicating with a space in the ahead turbine in front of the last stage of said turbine and conducting a portion of the steam from said space directly to the runner wheel in the casing of the reversing turbine working with the runner wheels in the ahead turbine.

5. A turbine aggregate for locomotives, comprising a multistage ahead turbine having a casing and a plurality of runner wheels, an astern turbine having a separate casing enclosing runner wheels for backward running, the last stage of the ahead turbine being subdivided into two halves of which the one is arranged in the casing of the ahead turbine and the other in the casing of the astern turbine, a shaft to which are fixed all the said runner wheels, and a conduit for supplying a portion of the steam from a space in front of the stages of the ahead turbine subdivided into two halves to the runner wheels of the half arranged in the astern turbine and working in parallel with the other half of said runner wheels arranged in the ahead turbine and impinged by the other portion of the steam.

6. A turbine aggregate for locomotives, comprising a turbine for forward running having a casing and a plurality of runner wheels, a pipe for supplying live steam to said turbine, a turbine for backward running having a separate casing, a pipe for supplying live steam to said turbine for backward running, one runner wheel of the last stage of the turbine for forward running inclosed in said separate casing, a shaft common to both turbines, means on said shaft between the turbines to transmit power to the locomotive, and a pipe communicating with a space in the turbine for forward running situated in front of the last stage of said turbine and conducting a portion of the low pressure steam from said space to the runner wheel which is arranged within the casing of the turbine for the backward running, the last mentioned runner wheel working in parallel with the runner wheels arranged within the turbine for forward running that are impinged by the portion of the low pressure steam that remains in the turbine for forward running.

In testimony whereof I affix my signature.
WALTER ANDERHUB.
